[57] CLAIM

The ornamental design for an ankle element of a shoe upper, as shown and described.

DESCRIPTION

FIG. 1 is a front and right side elevational view of an ankle element of a shoe upper showing my new design; FIG. 2 is a left side view thereof;

FIG. 3 is a top elevational view thereof;

FIG. 4 is a bottom elevational view thereof;

FIG. 5 is a front view thereof; and,

FIG. 6 is a rear view thereof.

The broken line showing of a shoe upper and sole in the figures is for illustrative purposes only and forms no part of the claimed design.
